UNITED STATES PATENT OFFICE.

EUGENE DANIEL, OF PARIS, FRANCE, ASSIGNOR TO ROXBURY CARPET COMPANY, OF BOSTON, MASSACHUSETTS.

DESIGN FOR CARPETS.

Specification forming part of Design No. 9,395, dated July 18, 1876; application filed July 5, 1876.
[Term of Patent 3½ years.]

To all whom it may concern:

Be it known that I, EUGENE DANIEL, of Paris, in the Department of Seine and Republic of France, have invented a new and original Design for Carpets, of which the following is a specification:

The nature of my design is fully shown in the accompanying photographic illustration.

I claim—

The design for carpets, as shown in the accompanying photographic illustration.

In testimony whereof I have signed my name to this specification in the presence of two subscribing witnesses,

EUGENE DANIEL.

Witnesses:

ROBT. M. HOOPER,
DAVID T. S. FULLER.
